Attorney, Agent, or Firm—Trexler, Bushnell, Giangiorgi & Blackstone, Ltd.[57] **CLAIM**

I claim the ornamental design for a CD clock, as shown.

DESCRIPTION

FIG. 1 is a left-front perspective view of a CD clock showing my new design;

FIG. 2 is a front elevational view thereof;

FIG. 3 is a rear elevational view thereof;

FIG. 4 is a top plan view thereof;

FIG. 5 is a bottom plan view thereof; and,
FIG. 6 is a left side elevational view thereof, the right side being a mirror image thereof.

The broken-line showings of a support stand in FIGS. 1-6 are for environmental purposes only and form no part of the claimed design.
